UNITED STATES PATENT OFFICE

143,786

DESIGN FOR A TOBACCO SMOKING PIPE FOR WOMEN

William Arnold, Washington, D. C.

Application May 16, 1945, Serial No. 119,567

Term of patent 3½ years

(Cl. D85—8)

To all whom it may concern:

Be it known that I, William Arnold, a citizen of the United States, residing at Washington, in the District of Columbia, have invented a new, original, and ornamental Design for a Tobacco Smoking Pipe for Women, of which the following is a specification, reference being had to the accompanying drawing, forming part thereof.

Figure 1 is a top plan view of a tobacco smoking pipe for women showing my new design.

Figure 2 is a side or edge elevational view.

Figure 3 is a front end view, that is a view of Figures 1 and 2, from left to right, with the hinged cap swung to open position to expose the bowl.

I claim:

The ornamental design for a tobacco smoking pipe for women, as shown.

WILLIAM ARNOLD.
